URETHRAL DILATOR-CATHETER OR SIMILAR ARTICLE

John Francis Carney, Joliet, Ill., assignor to
Morton-Norwich Products, Inc.

Filed June 30, 1971, Ser. No. 158,664

Term of patent 14 years

Int. Cl. D24—02
U.S. Cl. D83—12 A

FIG. 1 is a side elevational view of a urethral dilator-catheter showing my new design;

FIG. 2 is a sectional view of FIG. 1;

FIG. 3 is a top plan view; and

FIG. 4 is an end-elevational view.

I claim:

The ornamental design for a urethral dilator-catheter or similar article, as shown.
